DESIGN FOR A HANDLE

Philip Derham, Rosemont, Pa., assignor to Mastercraft Plastics Co. Inc., Jamaica, N. Y., a corporation of New York

Application September 29, 1947, Serial No. 141,642

Term of patent 7 years

(Cl. D44—29)

To all whom it may concern:

Be it known that I, Philip Derham, a citizen of the United States, residing at Rosemont, Montgomery County, State of Pennsylvania, have invented a new, original, and ornamental Design for a Handle, of which the following is a specification, reference being had to the accompanying drawing, forming part thereof.

Figure 1 is a front view of a handle, showing my new design;

Figure 2 is a side view;

Figure 3 is a rear view; and

Figure 4 is a cross-sectional view thereof taken on line 4—4 of Figure 1.

I claim:

The ornamental design for a handle, as shown.
PHILIP DERHAM.
